MODIFIED SWEEP CIRCUIT

William A. Miller, Port Jefferson, and Eugene R. Shenk, Brooklyn, N. Y., assignors to Radio Corporation of America, a corporation of Delaware

Application November 2, 1943, Serial No. 508,702

4 Claims. (Cl. 250—27)

1

The present invention relates generally to a method of and means for generating saw-tooth voltage waves. Circuits for generating saw-tooth voltage waves are generally referred to as "sweep circuits" because of the fact that the saw-tooth voltage wave is utilized to vary the voltage on the horizontal deflection plates of a cathode ray oscilloscope, as a result of which an electron beam "sweeps" or scans the fluorescent screen on the oscilloscope.

More specifically, the present invention provides a method of and a circuit arrangement for modifying the normally linear sweep or saw-tooth voltage wave-form in such manner that the voltage wave increases linearly to a particular point or voltage value, then remains stationary at this point or voltage value for a predetermined interval of time, and then increases again linearly for the normal duration of the saw-tooth voltage wave. The present invention permits an adjustment of the particular point or voltage value of the saw-tooth voltage wave-form at which the increase in voltage is stopped for the desired period of time.

Although it is known in the prior art to modify the wave-form of a normally linear saw-tooth generator, such known circuits have modified the saw-tooth wave-form at the expense of a net increase or decrease of the final saw-tooth voltage, or have caused a change in the slope of that portion of the saw-tooth wave which follows the modified portion. By means of the present invention, however, we are able to produce a saw-tooth wave which normally increases in value at a constant rate, and then stops increasing in voltage value at some point in the saw-tooth wave for a desired interval of time, after which the saw-tooth voltage wave-form continues normally to increase with the same slope as before the stoppage of the saw-tooth voltage wave. Moreover, by means of the present invention, the change in the saw-tooth voltage wave does not affect either the duration or the amplitude of the overall saw-tooth voltage wave. Putting it in other words, the end result of the modified saw-tooth voltage wave produced by the present invention insofar as duration or amplitude is concerned is the same as the saw-tooth voltage wave would have been without the modification.

A more detailed description of the invention follows in conjunction with a drawing, wherein:

Figure 1 illustrates, by way of example only, one circuit embodiment of the present invention for producing a modified saw-tooth voltage wave having the above mentioned characteristics, and

2

Figure 2 graphically illustrates the operation of the present invention by means of a series of curves X, Y and Z.

Graph X of Figure 2 illustrates the type of saw-tooth voltage wave obtained from the circuit of the invention. The ordinate represents voltage while the abscissa represents time. It is desired that the saw-tooth voltage wave increase linearly from a normal value to a particular point D at which it is desired that the voltage of the saw-tooth wave remain at rest for an interval T from D to F, after which the voltage wave-form should again increase linearly from point F to point G with the same slope that it had between the point of origin and point D. It should be noted that at point D the voltage of the saw-tooth wave increases rapidly by a value M, then remains at rest for a period T until the point F is reached, after which the normally linear increase in voltage of the saw-tooth wave is continued. It should be noted that the overall linear increase in voltage of the saw-tooth wave from the point of origin to point G is the same as would occur without the modification produced by the sudden increase in voltage at point D and the rest in the interval T. Before proceeding with a discussion of the circuit of Figure 2, it should at this time be noted that the time T at which the voltage of the saw-tooth wave remains at rest corresponds in time and duration to the rectangular pulse shown in line Z of Figure 2. It should also at this time be noted that the time interval of the saw-tooth voltage wave between the point of origin and the point G is equal to the duration of the negative pulse shown in line Y. The reason for this is described in greater detail in connection with the operation of the circuit diagram of Figure 1.

Referring to Figure 1, there are shown a pair 40 of vacuum tubes V1 and V2 having their cathodes directly connected together and in circuit with a common cathode resistor R5. The grid of tube V1 is connected directly to ground while its anode is connected to a source of positive polarizing potential Eb. The grid of tube V2 is connected through a pair of resistors R6 and R7 to the cathode of the same tube. The junction point of the resistors R6 and R7 is connected to terminal A to which the input pulse of line Z of Figure 2 is applied. The anode of tube V2 is connected through an adjustable resistor R2 to a positive source Eb. Between the anodes of the two tubes V1 and V2 there are provided a resistor R4, a pair of diodes V4 and V5, and a condenser 55 C1, as shown. Another diode V6 is connected

between ground and the junction point between diode V5 and condenser C1. A third vacuum tube V3 having a resistor R3 between its grid and cathode and a condenser C2 between its anode and cathode is connected from a point between the two diodes V4 and V5 to another source of positive potential +E. The positive voltage obtainable from source +E is less than that obtainable from source +E_B. The grid of tube V3 is connected through a condenser to terminal B to which a negative rectangular wave pulse generally of the form of graph Y of Figure 2 is supplied.

The operation of the circuit of Figure 1 in its three essential steps in the operation of the complete cycle will now be described. Starting with the quiescent condition before the application of any pulse to either terminals A or B, the vacuum tube V1 will be non-conducting while the vacuum tubes V2 and V3 will be conducting. In the second essential step in the cycle of operations, with the application of a negative rectangular wave pulse Y to terminal B, the vacuum tube V1 will still be non-conducting, the vacuum tube V2 will still be conducting, while the vacuum tube V3 will be in the non-conducting condition because of the application of a negative input pulse to its grid. In the third essential step of the cycle of operations, with the negative rectangular wave pulse Y still applied to terminal B and with the negative rectangular wave input pulse Z applied to terminal A, the vacuum tube V1 will become conducting while the vacuum tubes V2 and V3 will be non-conducting. The vacuum tube V3 will remain non-conducting until the end of the rectangular wave pulse Y applied to terminal B.

Considering the operation of Figure 1 in more detail, with particular reference to the various circuit elements, the vacuum tube V1 will be non-conducting and the vacuum tubes V2 and V3 will be conducting during the quiescent condition—that is, prior to the application of negative pulses to either of the terminals A and B. In this quiescent condition, it will be seen that the grid of tube V2 has no bias applied thereto, as a result of which current will flow from the positive source +E_B through resistor R2 and through the vacuum tube V2 to ground through the common bias resistor R5. The flow of current through resistor R5 will produce an IR drop therein which applies sufficient negative bias to the grid of tube V1 to cut-off the flow of anode current in this tube. Inasmuch as the negative rectangular wave pulse has not been applied to terminal B in this quiescent condition of operation, there will be no bias on the grid of tube V3 and this tube will also be conducting. As a result of the status of these three tubes, in this particular condition of operation, there will be a flow of current from the positive source +E_B through resistors R1 and R4 in series, through diode V4 and through vacuum tube V3 to the source +E. Source E, as before mentioned, has a positive value less than that of source E_B. As a result of this, a charge will build up on condenser C2, but this charge will be of small value due to the fact that the value of resistors R1 and R4 taken together is large compared to the internal impedance of the vacuum tube V3. This residual charge will always be on the condenser C2 and is indicated by the small positive amount on the ordinate above the reference line 0 in graph X of Figure 2. This ordinate represents the voltage on the condenser C2, and is labeled E_{C2}. It will thus be seen that the saw-

tooth sweep voltage starts with a small positive potential. In the next essential step in the operation representing the condition with only the negative pulse applied to terminal B (note graph Y of Figure 2), this negative pulse will bias the tube V3 to anode current cut-off, as a result of which the charge on condenser C2 will start to build up linearly.

In this step in the cycle of operation, tube V2 is still conducting and tube V1 non-conducting. At some later time, when it is desired to stop the increase in voltage on the condenser C2, for a desired period of time, representing the third essential step in the cycle of operation of Figure 1, there is applied to terminal A a negative input pulse of a magnitude sufficient to cut off the flow of anode current through tube V2. (Note graph Z of Figure 2.) The application of a negative input pulse to terminal A causes the tube V2 to be non-conducting as a result of which the flow of current through R5 produced by the current flow in tube V2 ceases, thus permitting tube V1 to conduct. Since the negative input pulse applied to terminal B is of longer duration than that applied to terminal A, it will be seen that in this particular step in the cycle of operations, tubes V2 and V3 are non-conducting while tube V1 is conducting. Under this condition of operation, in which tube V1 is conducting, there will be a flow of current through resistor R1, in turn causing a decrease in the voltage applied to the anode of diode V4 through resistor R4. The voltage now available on the anode of diode V4 is less positive than the voltage on the cathode of the same diode, as a result of which the diode V4 will cease conducting, thus stopping the building up of the charge on the condenser C2 over the path which included the diode V4 and resistors R4 and R1 in series. At the same time that diode V4 ceases conducting, there will be a sudden rise in the potential of the charge on condenser C2 represented by the amount M in graph X of Figure 2, due to the fact that when tube V2 ceases conducting there is a rise in potential applied to the circuit including resistor R2, condenser C1, diode V5 and condenser C2 in series. This rise in potential makes diode V5 conduct and charges condensers C2 and C1 in series. Condenser C2 will remain charged to the suddenly increased amount represented by point D in graph X of Figure 2, for the time interval T corresponding to the duration of the negative input pulse applied to terminal A (note Figure 2). When the negative input pulse applied to terminal A ceases, vacuum tube V2 will again conduct and bias vacuum tube V1 to the non-conducting state.

During the time interval of the negative input pulse Z applied to terminal A, it will be noted that the charge on condenser C2 remains constant as represented by the horizontal line between points D and F on graph X of Figure 2. The flow of current through V2 after the termination of the negative input pulse applied to terminal A will now reduce the voltage available in the path including R2, C1 and diode V5 to a positive value less than the value of source +E, as a result of which the diode V5 will cease conducting and condenser C1 will discharge through diode V6. The time required for the sudden increase in voltage on condenser C2 during the time interval when diode V5 is conducting depends upon the time constant of the circuit including resistor R2 and condensers C1 and C2; while the amount of sudden increase in voltage on condenser C2 de-

pends upon the ratio of C_2 to C_1 and upon the value of R_2 . When diode V_5 becomes non-conducting, simultaneously therewith diode V_4 becomes conducting to reestablish a charging path for condenser C_2 through diode V_4 and resistors R_4 and R_1 in series. The reestablishment of this charge path for condenser C_2 causes the charge on condenser C_2 to increase linearly from point F to the end of the cycle of operations represented by point G in Figure 2. It should be noted that except for the time interval T, the saw-tooth wave is linear and represented by a single straight line.

In the design of the circuit of Figure 1, the time constants and values of the various elements are such that the height M of Figure 2 representing the sudden increase in voltage on C_2 at point D and the rest period T during which the charge on condenser C_2 remains constant are in the same ratio as the height of the saw-tooth wave at time G and the duration of the complete saw-tooth wave represented by the time of the negative input pulse on graph Y.

It will be noted that the time T during which the saw-tooth wave is modified and during which the charge on condenser C_2 remains constant depends upon the position of the negative pulse Z supplied to terminal A and its duration. By moving the position of the pulse applied to terminal A, we can thus modify the saw-tooth wave at any desired point in its cycle in accordance with graph X of Figure 2.

One use of the present invention, given by way of example only, is in connection with a radio locating and detecting system employing antenna lobe switching. In such a system, pulses of radio frequency energy are sent out in all four quadrants of a circle and it is important to distinguish on the oscilloscopes between pulses received during the different quadrants of the lobe switcher. By means of the present invention, one is able effectively to displace on the oscilloscope one received pulse with respect to another received pulse in an opposite quadrant. For an example of an antenna lobe switching system of the prior art, reference is made to Lindenblad application, Serial No. 454,661, filed August 13, 1942, and to Miller copending application, Serial No. 473,801, filed January 28, 1943, U. S. Patent 2,422,361, issued June 17, 1947.

What is claimed is:

1. The method of generating a modified saw-tooth wave by means of a circuit including a condenser, which comprises linearly charging said condenser to a desired point in the charge cycle, suddenly increasing the charge on said condenser by a desired amount, maintaining constant the charge on said condenser for a predetermined interval of time after the sudden increase of the charge, and then again linearly charging said condenser at the same rate as before.

2. The method of generating a modified saw-tooth wave by means of a circuit including a condenser, which comprises linearly charging said condenser to a desired point in the charge cycle, suddenly increasing the charge on said condenser by a desired amount, maintaining constant the charge on said condenser for a predetermined interval of time after the sudden increase of the charge, and then again linearly charging said condenser at the same rate as before, the ratio which the amount of said sudden increase in charge on said condenser bears to said predetermined time interval being the same as the ratio which the total maximum charge on said con-

denser bears to the total time it takes for said condenser to reach said maximum charge.

3. A generator of modified saw-tooth waves comprising first and second vacuum tubes each having a cathode, a grid and an anode, a direct connection between the cathodes of said two tubes, a common cathode resistor for said two tubes one terminal thereof being grounded, separate resistive connections from the anodes of said two tubes to a source of positive unidirectional polarizing potential, a connection from the grid of said first tube to ground, a resistive connection from the grid of said second tube to its cathode, whereby said second tube normally draws current and biases said first tube to anode current cut-off, a circuit between the anodes of said two tubes, a condenser connected between said circuit and a second source of positive unidirectional potential, the positive potential of said last source being smaller in magnitude than the positive potential of said first source, a vacuum tube shunting said condenser, a connection for supplying to said vacuum tube a negative pulse of sufficient magnitude to render said last vacuum tube nonconducting, to thereby enable a charge to build up on said condenser over a circuit including the anode resistive connection of said first tube, and a circuit for supplying a negative pulse to the grid of said second tube of a duration less than that of said other negative pulse and of a magnitude sufficient to bias said second tube to cut-off, as a result of which said first tube becomes conducting for the interval of said smaller duration negative pulse, and the shape of the saw-tooth wave produced by said generator is modified.
4. A generator of modified saw-tooth waves comprising first and second vacuum tubes each having a cathode, a grid and an anode, a direct connection between the cathodes of said two tubes, a common cathode resistor for said two tubes one terminal thereof being grounded, separate resistive connections from the anodes of said two tubes to a source of positive unidirectional polarizing potential, a connection from the grid of said first tube to ground, a resistive connection from the grid of said second tube to its cathode, whereby said second tube normally draws current and biases said first tube to anode current cut-off, a circuit between the anodes of said two tubes, comprising the series connection of a resistor, a first diode, a second diode and a first condenser, said first resistor of said series connection being directly connected to the anode of said first tube, while said first condenser is directly connected to the anode of said second tube, the cathodes of said two diodes being directly connected together, a third diode connected between ground and the junction point of said second diode and first condenser, a second condenser connected from the cathodes of said first and second diodes to a second source of positive unidirectional potential, the positive potential of said last source being smaller in magnitude than the positive potential of said first source, a third vacuum tube having its anode connected to one terminal of said last condenser and its cathode connected to the other terminal thereof, a connection for supplying to the grid of said last vacuum tube a negative pulse of sufficient magnitude to bias the tube to anode current cut-off for the duration of the pulse to thereby enable a charge to build up on said second condenser over a path including the anode resistive connection of said first tube and the resistor and first diode of said series connection, and a circuit for supply-

7
ing a negative pulse to the grid of said second tube of a duration less than that of said other pulse and of a magnitude sufficient to bias said second tube to cut-off, as a result of which said first tube becomes conducting and produces an IR drop in its anode circuit of sufficient value as to interrupt the charging path for said second condenser for the interval of said smaller duration negative pulse, said second condenser having its charge suddenly increased when said charging path is interrupted, over a path including the second diode, the first condenser and the anode resistive connection of said second tube, after which the charge on the second condenser remains constant for the time during which said second tube is cut off, said second tube again drawing current upon the termination of said smaller duration negative pulse, as a result of which said first tube becomes non-conducting and the charge on said second condenser again builds up to its maximum value, the termination of said

10 longer duration negative pulse permitting said third tube to draw current and discharge said second condenser.
